UNITED STATES PATENT OFFICE

106,685

DESIGN FOR A CONSOLE EXTENSION TABLE

Clarence B. Gaeke, Dayton, Ohio, assignor to The Mutual Furniture Manufacturing Company, Miamisburg, Ohio, a corporation of Ohio

Application July 13, 1937, Serial No. 70,396

Term of patent 3½ years

To all whom it may concern:

Be it known that I, Clarence B. Gaeke, a citizen of the United States, residing at Dayton, in the county of Montgomery and State of Ohio, have invented a new, original, and ornamental Design for a Console Extension Table, of which the following is a specification, reference being had to the accompanying drawings, forming a part thereof.

In the accompanying drawings Fig. 1 is a perspective view of the table showing my new design, with the hinged portion of the table top in its extended position and supported on the two swing legs; Fig. 2 is a side elevation of the table extended as shown in Fig. 1; Fig. 3 is a side elevation of the table with the hinged portion of the table top folded on the main portion of the table and the swing legs folded against the stationary rear legs; Fig. 4 is a view similar to Fig. 3 with the hinged portion of the table top in an elevated position; and Fig. 5 is a front elevation of the table with the parts in the position shown in Fig. 3.

I claim:

The ornamental design for a console extension table, as shown.

CLARENCE B. GAEKE,
